UNITED STATES PATENT OFFICE.

ERNEST F. YOST AND WILLIAM H. SMITH, OF NEW YORK, N. Y.

DESIGN FOR AN ELECTRIC-CELL BODY.

SPECIFICATION forming part of Design No. 33,231, dated September 18, 1900.

Application filed June 28, 1900. Serial No. 21,996. Term of patent 7 years.

To all whom it may concern:

Be it known that we, ERNEST F. YOST and WILLIAM H. SMITH, of the borough of Brooklyn, city of New York, State of New York, have 5 invented a new and original Design for Electric-Cell Bodies, of which the following is a specification.

Our design relates to the exterior configuration of the cell-body and is shown in perspective in the accompanying drawing. Said configuration shows a quadrangular pyramidal frustum, the faces of which, as A and B, are flat. From the inclined faces B protrude tu-

bular projections G G. A portion C of the cell-body is hollow or open and is bounded by 15 inclined walls D E and the connecting or cross wall F.

We claim—

The design for an electric-cell body substantially as herein shown and described.

ERNEST F. YOST.
WILLIAM H. SMITH.
